UNITED STATES PATENT OFFICE

CHARLES F. HENNEY, OF DAYTON, OHIO, ASSIGNOR TO FRIGIDAIRE CORPORATION, OF DAYTON, OHIO, A CORPORATION OF DELAWARE

REFRIGERATING APPARATUS

Application filed July 17, 1930. Serial No. 468,555.

This invention relates to refrigerating apparatus, and more particularly to cooling units of the flooded type adapted for use in refrigerator cabinets.

One of the objects of the present invention is to insure the free and natural circulation of refrigerant in the ducts of an evaporator of the type in which the ducts depend from and receive liquid refrigerant from a reservoir.

10 In certain types of refrigerating systems, a blanket of oil floats on the liquid refrigerant in the reservoir of the evaporator.

Another object of the present invention is to intensify the agitation of this blanket of 15 oil.

A still further object of the invention is to provide a cooling unit of large capacity which will occupy little space and which may be easily assembled.

20 Further objects and advantages of the present invention will be apparent from the following description, reference being had to the accompanying drawings, wherein a preferred type of the present invention is clearly 25 shown.

In the drawings:

Fig. 1 is a front view of the improved cooling unit together with a diagrammatic representation of the remainder of a refrigeration 30 system;

Fig. 2 is a cross section of the header or tank portion of the cooling unit;

Fig. 3 is a side view of the cooling unit;

Fig. 4 shows the cooling unit mounted in a 35 commercial refrigerator cabinet;

Fig. 5 is a sectional view on the line 5—5 of Fig. 2;

Fig. 6 shows a front view of a modified form of cooling unit, and

40 Fig. 7 is a side view of the modified form.

Referring to the drawings, there is shown diagrammatically for illustrative purposes, a refrigerating system of the compressor-condenser-expander type including a compressor 45 21 for compressing the refrigerant, preferably sulphur dioxide, and for forwarding it to the condenser 22 where it is liquefied and collected in the receiver 23. The actuating means for the compressor comprises a motor 24 connected by pulley and belt means 25

to the compressor. A supply conduit 26 supplies liquid refrigerant to the evaporator or cooling unit 27 where the liquid refrigerant vaporizes because of the absorption of heat and is returned to the compressor through 55 the return conduit 28. A pressure responsive switch means 29 is preferably connected to the return conduit 28 for controlling the motor 24 to provide alternating operating and idle periods of the compressor according to 60 the pressure and consequently the temperature of the evaporator.

The cooling unit 27 comprises a header or tank portion 30 which forms a reservoir for liquid refrigerant and a plurality of looped 65 ducts 31 which carry a plurality of spaced parallel vertical cross fins 32 for increasing the area of heat transfer. Each of the ducts 31 has one end connected into the lower portion of the header or tank member as 70 shown at 33 from which point the duct extends downwardly a suitable distance forming the drop tube portion and then is bent through 90° as shown at 34 from which point it extends horizontally through the fins 32 75 and, upon passing through, its direction is reversed and the duct extends upwardly passing backwardly and forwardly horizontally through the banks of fins in serpentine fashion, reversing its direction after each pass 80 through the banks of fins in serpentine fashion, header or tank member 30 at its side as shown at 36 (Figs. 1 and 5). The ducts 31 throughout their winding path each lie in a single plane, the ducts being arranged side by side 85 in parallel planes.

Within the header or tank member 30 is a float member comprising the float ball 50 and the float ball arm 51 which regulates the level 90 52 of liquid refrigerant within the cooling unit. The float ball arm 51 is pivoted at 53 and operates a needle valve 54 which controls the supply of liquid refrigerant coming through the conduit 26. The serpentine portion of the duct 31 preferably connects into the header substantially at the level of the liquid refrigerant (see Fig. 5), which in the preferred type of header is maintained at approximately the center line of the tank member 30. Oil, which is delivered with the 95 100

liquid refrigerant from the crank case of the compressor, tends to accumulate within the cooling unit and floats as a layer on the surface 52 of the liquid refrigerant. By connecting the end of the serpentine portion of the duct 31 into the header or tank member at substantially the level of the liquid refrigerant, the gaseous refrigerant entering the header or tank member, bubbles through this layer of oil indicated at 55 and intensifies the agitation thereof.

By increasing the agitation of the oil, gaseous refrigerant can more readily pass therethrough and the oil is carried more readily with the gaseous refrigerant to the outlet of the evaporator. In this manner only a thin blanket of oil will float on the liquid refrigerant. By arranging so that only a thin blanket of oil is present, the flow of refrigerant through the evaporator is more even and therefore the temperature can be more readily regulated. Also, the system operates more efficiently with a thinner blanket of oil because gaseous refrigerant will more readily pass through the thin blanket and in this manner the back pressure above the blanket will be relatively close to the pressure of the refrigerant below the blanket. Thus, the compressor operates at a higher and therefore a more efficient back pressure.

The fins 32 are made in sections 37 each receiving the serpentine portion of a pair of the looped ducts 31 and have elongated holes 38 each having a flange bordering each of the holes. These elongated holes receive the serpentine looped portions 40 of the duct 31 as shown in Figs. 1 and 3.

In manufacturing cooling units on a commercial scale, it becomes necessary to provide different sizes and for this purpose fins have been made in sections so that the number of different parts required for different sizes is reduced to a minimum. For a small size cooling unit two of the sections 37 of fins and four of the looped ducts 31 together with a short header or tank member may be used, making a cooling unit of approximately one-half the size of the unit shown in Fig. 3. For a slightly larger cooling unit three sections and six of the looped ducts may be used. The large size of cooling unit is shown in Fig. 3 and contains four sections of fins and eight of the looped ducts with the correspondingly longer header. If desired, a longer tank member with more sections and looped ducts may be used.

In manufacturing the cooling unit the looped ducts 31 are first bent into the form shown in Fig. 1. A pair of these bent ducts are taken and a plurality of the fins 32 are pressed upon the bent ducts after which the now completed section is placed side by side with several other sections which are then connected together by suitable means such as the strips 41 and 42 which are soldered, weld-

ed or secured in any other suitable manner to the upper and lower edges of the end fins of each section. This assembly is then dip-soldered and finally the ends of the looped duct 31 are connected into the header at the points 33 and 36 (Fig. 1) and silver-soldered to make a permanent joint.

It is often desired in some types of refrigerator cabinets to have a cooling unit which may be placed within a narrow space. Bearing this in mind applicant has shown a modification (Figs. 6 and 7) in which the header or tank member 61 is placed parallel to the serpentine ducts 62 and the sections of fins 63.

The outer drop tubes 64 depend from the lower portion of the header or tank member, extending downwardly, passing outside of the protruding portions 65 of the serpentine portion of the ducts 62 and at their lower ends 66 make a right angle turn and extend horizontally and then upwardly in serpentine fashion and enter the header or tank member 61 at its end portion. The inner ducts 67 depend from the bottom portion of the header or tank member 61 and extend downwardly, passing inside of the protruding ends of each of the serpentine portions of the inner ducts, and at the lower end of the drop portion, of each of the inner ducts make a right angle turn, extending horizontally, and then upwardly, in serpentine fashion, and connect into the end of the header or tank member 61 in a manner similar to that described for the ducts 62.

It has been found desirable to keep the difference in height between the upper connection and lower connection of all the ducts the same. In this modification the two center ducts have had their drop tube connected at the extreme bottom portion of the header and their top portion somewhat below the center of the end of the header whereas the side ducts have their drop tubes connected at a more remote point from the bottom point of the header and have their upper ends connected substantially at the center line of the header or tank member.

The fins in the modifications shown in Figs. 5 and 6 are assembled upon the serpentine ducts in sections which are connected together and finally the ends of the serpentine ducts are connected into the header in a manner similar to that explained for the modification shown in Figs. 1 to 4 inclusive.

By applicant's construction a natural circulation is provided. The cold liquid refrigerant first passes down the finless drop tube portion of the ducts, which portion absorbs little heat, and then passes up through the finned serpentine portion where the liquid refrigerant absorbs a large amount of heat, causing a portion of the liquid to be changed into gaseous refrigerant, which, like the warmed liquid refrigerant, has a strong tendency to rise, thereby providing a rapid, de-

pendable, natural, circulation which increases the capacity of the cooling unit by facilitating more rapid heat transfer.

In Fig. 4, for illustrative purposes, an installation of applicant's cooling unit within a commercial refrigerator cabinet 57 is shown. Air within the top of the refrigerator passes downwardly between the fins 32 and gives its heat up to the fins and thus being cooled, passes downwardly to the bottom of the refrigerator to cool articles stored in this portion of the refrigerator and passes upwardly to the top of the refrigerator and again returns to the cooling unit. By using a cooling unit with a large amount of vertical surface, frosting of the cooling unit is prevented as well as the excessive removal of moisture from the articles of food stored in the refrigerator.

While the form of embodiment of the invention as here disclosed constitutes a preferred form, it is to be understood that other forms might be adopted, all coming within the scope of the claims which follow.

What is claimed is as follows:

1. In a cooling unit for refrigerating apparatus, the combination of a header adapted to contain liquid refrigerant and a floating layer of lubricant, means for regulating the level of the liquid refrigerant, and a looped duct having one end depending from the header and connected thereto to receive liquid refrigerant therefrom and having the other end connected into the header at the liquid refrigerant level.

2. In a cooling unit for refrigerating apparatus, the combination of a header adapted to contain liquid refrigerant and a floating layer of lubricant, means for regulating the level of the liquid refrigerant, and a looped duct having one end depending from the header and connected thereto to receive liquid refrigerant therefrom, said duct extending downwardly a suitable distance and then extending upwardly in serpentine fashion and having its other end connected into the header at the liquid refrigerant level.

3. In a cooling unit for refrigerating apparatus, the combination of a tank member adapted to contain liquid refrigerant, means to regulate the level of the liquid refrigerant within the tank member and means to provide a natural circulation of said liquid refrigerant comprising a looped duct having one end depending from the bottom portion of said tank member and having the other end connecting into said tank member substantially at the level of the liquid line.

4. In a cooling unit for refrigerating apparatus, the combination of a tank member adapted to contain liquid refrigerant, means to regulate the level of the liquid refrigerant within the tank member and means to provide a natural circulation of said liquid refrigerant comprising a looped duct having

one end depending from the bottom portion of said tank member and having the other end connecting into said tank member substantially at the level of the liquid line and having a plurality of fins thereon for absorbing heat. 70

In testimony whereof I hereto affix my signature.

CHARLES F. HENNEY.
